(57) **CLAIM**

We claim the ornamental design for a saw blade, as shown and described.

DESCRIPTION

FIG. 1 is a perspective view of a saw blade according to one embodiment.

FIG. 2 is a side view of the saw blade of FIG. 1.

FIG. 3 is a first end view of the saw blade of FIG. 1.

FIG. 4 is a second end view of the saw blade of FIG. 1.

FIG. 5 is a top view of the saw blade of FIG. 1.

FIG. 6 is a bottom view of the saw blade of FIG. 1.

FIG. 7 is a perspective view of a saw blade according to another embodiment.

FIG. 8 is a side view of the saw blade of FIG. 7.

FIG. 9 is a first end view of the saw blade of FIG. 7.

FIG. 10 is a second end view of the saw blade of FIG. 7.

FIG. 11 is a top view of the saw blade of FIG. 7.

FIG. 12 is a bottom view of the saw blade of FIG. 7.

FIG. 13 is a perspective view of a saw blade according to another embodiment.

FIG. 14 is a side view of the saw blade of FIG. 13.

FIG. 15 is a first end view of the saw blade of FIG. 13.

FIG. 16 is a second end view of the saw blade of FIG. 13.

FIG. 17 is a top view of the saw blade of FIG. 13.

FIG. 18 is a bottom view of the saw blade of FIG. 13.

FIG. 19 is a perspective view of a saw blade according to another embodiment.

FIG. 20 is a side view of the saw blade of FIG. 19.

FIG. 21 is a first end view of the saw blade of FIG. 19.

FIG. 22 is a second end view of the saw blade of FIG. 19.

FIG. 23 is a top view of the saw blade of FIG. 19; and,

FIG. 24 is a bottom view of the saw blade of FIG. 19.

The broken away symbols in the drawings indicate the appearance of any portion of the saw blade between the break lines forms no part of the claimed design.
